UNITED STATES PATENT OFFICE

2,644,969

BABY BOOTEE STRETCHER

Alva B. Reser, Long Beach, Calif.

Application August 6, 1951, Serial No. 240,492

1 Claim. (Cl. 12—128)

1

This invention relates to an improved type of stretcher for soft woolen articles, such as baby booties, and preferably those which are knitted.

An object of my invention is to provide an improved, simple and inexpensive bootie stretcher which can be quickly and easily adjusted to different lengths, as required, to stretch booties to the desired size.

Another object of my invention is to provide an improved bootie stretcher of the character stated, in which the heel section of the stretcher is adjustably mounted on a tongue which projects from the toe section of the stretcher, thus achieving an increase in the over all length of the stretcher.

A feature of my invention is to provide an improved bootie stretcher of the character stated, which can be easily moulded from an inexpensive material, such as plastic, and the like.

Other objects, advantages and features of invention may appear from the accompanying drawing, the subjoined detailed description and the appended claim.

In the drawing:

Figure 1 is a side elevation of my bootie stretcher.

Figure 2 is a top plan view of the same, in disassembled position.

Figure 3 is a longitudinal sectional view of my bootie stretcher.

Referring more particularly to the drawing, my improved bootie stretcher 1 is preferably cast from a light and inexpensive material, such as certain of the plastics. The stretcher includes a hollow toe section 2, which conforms generally in shape to the toe portion of an infant's bootie. The toe portion 2 also includes a bottom wall 3, a continuation of which forms a tongue 4, projecting rearwardly from the toe section. An elongated slot 5 is formed in the tongue 4 for the purposes of adjustment, as will be further described.

The heel section 6 is also hollow, consisting generally of a bottom wall 7 which is provided with a rectangular recess 8, generally shaped to accurately fit the contour of the tongue 4. The tongue 4 can slide in the recess 8 and is accurately

2

guided by the side edges of the recess, thus holding the toe section 2 in correct alignment with the heel section 6.

A set screw 9 is threaded into the bottom wall 7 of the heel section 6, and this set screw extends through the slot 5, and when the set screw is tightened, it will bear against the top edge of the tongue 4, thus holding this tongue in adjusted position relative to the heel section 6.

It will thus be evident that the tongue and heel sections can be moved longitudinally relative to each other, thus increasing or decreasing the over all length of the bootie stretcher.

By loosening the set screw 9, the heel section 6 can be moved on the tongue 4 to the desired position. Thereafter, the set screw 9 is tightened, and the over all length of the bootie stretcher will thus be set.

Having described my invention, I claim:

A baby bootie stretcher comprising a hollow toe section shaped to fit the toe of a bootie, a bottom wall on said toe section, a tongue projecting rearwardly from said bottom wall, a hollow heel section the top of said heel section being open, a bottom wall on said heel section, the last named bottom wall having a recess formed therein shaped to fit and receive said tongue the depth of said recess being equal to the thickness of said tongue, said tongue having an elongated slot formed therein, a set screw threaded into the bottom wall of the heel section, said set screw extending through said groove, and said set screw bearing against the tongue to hold the tongue in adjusted position in said recess.

ALVA B. RESER.
